United States Patent

Des. 240,418
Patented July 6, 1976

240,418

BICYCLE

Tetsuo Hirano, Hammatsu, Japan, and Danny H. Shumate, La Mirada, Calif., assignors to U.S. Suzuki Motor Corporation, Santa Fe Springs, Calif.

Continuation-in-part of abandoned design application Ser. No. 381,043, July 20, 1973. This application Apr. 23, 1975, Ser. No. 570,732

Term of patent 14 years

Int. Cl. D12—11

U.S. Cl. D12—111

FIG. 1

FIG. 2

FIG. 3FIG. 4FIG. 1 is a side elevational view of a bicycle embodying our new design;

FIG. 2 is a front elevational view thereof;

FIG. 3 is a side elevational view thereof, opposite to that shown in FIG. 1; and

FIG. 4 is a top plan view thereof.

This application is a continuation-in-part of design application Ser. No. 381,043, filed July 20, 1973, and now abandoned.

We claim:

The ornamental design for a bicycle, substantially as shown and described.
